C. A. CAMPBELL,
HORSESHOE,
APPLICATION FILED MAR. 12, 1915.

1,177,481.

Patented Mar. 28, 1916.

Inventor-Charles A. Campbell by his Attorney
Hanson & Hanson

UNITED STATES PATENT OFFICE.

CHARLES A. CAMPBELL, OF PHILADELPHIA, PENNSYLVANIA.

HORSESHOE.

1,177,481.

Specification of Letters Patent.

Patented Mar. 28, 1916.

Application filed March 12, 1915. Serial No. 13,905.

To all whom it may concern:

Be it known that I, CHARLES A. CAMPBELL, a citizen of the United States, residing in Philadelphia, Pennsylvania, have invented certain Improvements in Horseshoes, of which the following is a specification.

My invention relates to horseshoes of the all metal type, and the object of my invention is to provide a horseshoe of this character with a lower or wearing face which will decrease the tendency of the shoe to slip or slide upon paved road surfaces, and will furnish the shoe with an improved bearing surface. I have found that if a shoe be provided, at the toe and heel portions, with suitable pockets or pocket-forming depending portions, snow or dirt will pack therein when the shoe is in use, and that said packed snow or dirt will provide rough gripping surfaces, and take the place of ordinary calks. Pockets for this purpose may be formed in different ways, but as the result of a long series of experiments, I have devised the construction hereinafter described, and find it peculiarly well suited to most normal conditions.

A further object of my invention is to provide a shoe of this character, having the improved grit retaining pockets, that may be readily bent, cold or hot, for the purpose of fitting it to wide or narrow hoofs, without distortion and without closing the nail holes initially formed therein.

These and other features of my invention are more fully described hereinafter, reference being had to the accompanying drawings, in which:

Figure 1, is a plan view of the lower or bearing face of one form of horseshoe embodying my invention; Fig. 2, is a sectional view on the line 2—2, Fig. 1; Fig. 3, is a sectional view on the line 3—3, Fig. 1; Fig. 4, is a sectional view on the line 4—4, Fig. 1; Fig. 5, is a sectional view on the line 5—5, Fig. 1; Fig. 6, is a view similar to Fig. 1, illustrating a slightly modified construction within the scope of my invention, and Fig. 7, is a view similar to Figs. 1 and 6, illustrating another arrangement within the scope of my invention.

My improved shoes are provided with means at the toe portions and at the heels that will serve as retaining pockets in which snow or dirt will pack when the shoe is in

use; such packing of snow or dirt serving to provide a rough gripping surface.

In the form of horseshoe shown in Fig. 1, an isolated pocket 1 is provided at the toe of the shoe. This pocket is formed by transverse depending walls 2, 2^a, at the forward outer portion of the same and at the inner portion thereof respectively; such walls conforming to the curvature of the forward or toe portion of the shoe and having their outer surface slightly beveled or converging inwardly so that the extreme width of the pocket formed by these walls longitudinally of the shoe at their bearing surface is less than the toe portion of the shoe with which they are integrally connected. These transverse depending walls 2, 2^a, are joined by end walls 3 substantially parallel with the longitudinal axis of the shoe, and the outer surface of said end walls may be beveled to the same degree as the transverse walls. The inner surfaces of the several walls forming this toe pocket are also slightly beveled; such beveling adding to the effective use of the structure by giving the walls a comparatively sharp contacting surface for engagement with the ground and being also desirable in the manufacture of the shoe since the latter is a drop forging.

The quarters or branches 4 of the shoe extend rearwardly in the usual curved lines to conform with the hoof of a horse, and are substantially the same width throughout and of the same thickness; such quarters terminating in rounded heels 5. The quarters are punched as indicated at 6 for the reception of nails for securing the shoe to the hoof in the usual manner, but the usual creasing or fullering is omitted.

In the form of shoe illustrated in Fig. 6, one of the side walls forming the toe pocket and paralleling the longitudinal axis of the shoe; that indicated at 3^a, for instance, is thickened outwardly as clearly indicated at 7 in the drawings, for the purpose of providing additional weight; such thickened portion when the shoe is applied to the hoof lying on the outside or to the right of shoes for the right feet, and to the outside or left of shoes for the left feet, and is designed to add a little weight to the hoof in horses which wear the shoes on the side in order that any tendency of the horse to walk unevenly may be avoided and relieve the mus-

cles that are strained when the shoe is only worn on one side. In addition, it adds extra wearing material to the side walls of the toe pocket without, however, affecting the 15 value and utility of such toe pocket.

At the termination of the quarters I provide snow and dirt retaining means as shown in Figs. 1, 2, 3, *et seq.*, and these 20 may be in the form of depending projections or calks 8 set diagonally with respect to the longitudinal axis of the shoe to avoid catching in the joints of paving, or as shown in Fig. 7, these depending retaining means 25 may be in the form of pockets 9; continuous depending walls being carried by the shoe adjacent the heels to form the same.

In the form of shoe shown in Fig. 1, I 30 provide sets of three depending projections or calks 8 adjacent the end of each quarter or branch, and these calks are set inward from the extreme end of the heel so as to bring the support of the hoof afforded thereby forward of the heel and avoid pressure on the point of the latter. These 35 calks or projections depend from the under surface of the shoe to the same depth as the walls of the toe pocket so that the bearing surfaces of the same are in the same plane as the bearing surfaces of the walls 40 at the toe of the shoe forming such toe pocket. Such depending projections or calks have beveled walls as indicated, and they are narrower at their bearing surface than at the point of junction with the quarters or branches of the shoe, as clearly indicated in the drawings.

In the form of horseshoe shown in Fig. 6, the outer portion of the shoe; that is to 45 say, the right hand branch or quarter of a right shoe and the left hand branch or quarter of a left shoe, is provided with three depending projections or calks of the same character as illustrated in Figs. 1, 2, *et seq.*, while the opposite side of the shoe 50 is only provided with two calks, which may be slightly thinner. The additional calk on the outer branch or quarter of the shoe adds weight on one side of the shoe in connection with the increased weight of the thickened wall 3^a of the toe pocket, and the 55 omission of a calk on the opposite branch or quarter of the shoe lightens the opposite side of the shoe so that horses tending to wear their shoes unevenly may have this defect corrected by the employment of a shoe of this character.

In the structure shown in Fig. 7, the 60 heel portions of the shoe are provided with pockets of a character substantially like that shown at the toe portion of the shoe; such heel pockets being made up of depending walls 8^a which follow the curvature of the branch or quarter at the heel portion of the shoe and are joined by diagonally positioned walls 8^b which lie substan-

tially in the same position as the outside or terminal calks of the sets shown in Fig. 1. In addition, in the structure shown in Fig. 7, I may provide the toe portion with a plurality of longitudinal depending walls 70 3^b intermediate the end walls 3 whereby a plurality of pockets 1^a are formed at such point. All of these pockets will have beveled walls as described, facilitating the withdrawal of the dies in the course of 75 manufacture.

An important feature of my invention lies in in the fact that a shoe made in accordance with my invention and having the depending pocketed portions in the same plane at toe and heels, providing an even bearing surface, has unobstructed branches or quarters intermediate these pocketed portions, which branches or quarters are of the same thickness and of substantially the same width. The nail holes being set inwardly to an extent sufficient to provide a substantial body of material well outside the nail holes and the creasing or fullering being omitted, there will be no danger of 80 closing such nail holes or of interfering with the proper driving of nails through the same into the hoof when the shoe is shaped cold to conform to peculiarites of 85 the hoof; a condition to which my improved 90 construction particularly lends itself.

The toe pocket is of substantial depth, and receives and retains snow or dirt, which 95 packs firmly therein and forms the bearing surface for the toe portion of the shoe, and the transverse walls 3 prevent the packed material from washing through or away from the pocket in wet weather. The calks 100 adjacent the heel will also retain a great deal of grit and road material; larger portions wedging between the same holding finer particles in place. The wear at the toe incident to the use of the shoe in the travel of the horse comes mainly upon the 105 forward depending wall 2, which wall, extending substantially the full width of the toe portion of the shoe, aids in providing at that point a wide, even bearing.

In the modification shown in Fig. 7, the 110 additional longitudinal walls 3^b interposed between the walls 2 and 2^a strengthen the construction and divide the pocket into smaller sections which, in some instances, 115 may more readily retain the packed snow or dirt.

The shoe can be made by drop-forging, and it will be noted that the branches or quarters of the shoe are free from projections, and consequently there is nothing to interfere with the bending or shaping of 120 the shoe by the blacksmith in fitting the same to the horse, either hot or cold.

As this application possesses matter in common with an application filed by me February 4, 1914, Serial No. 816,588, it is 125 130

to be treated as a continuation of said prior application as far as the common subject-matter is concerned.

No claim is made herein to the structure 5 shown in Fig. 6, the same forming the subject of an application for patent filed by me April 20, 1915, Serial No. 22,698.

I claim:

1. As a new article of manufacture, a 10 horseshoe of substantially uniform thickness throughout its entire extent having separate heel extensions, with a plurality of walls depending from the lower surface of said shoe at the central portion of the toe 15 thereof to form an isolated pocket for the reception of snow, dirt, etc., to provide a bearing or wear surface; certain of said walls following the inner and outer contour of the shoe, the quarters of said shoe being 20 substantially unobstructed rearwardly from said toe pocket, and projections depending from said quarters forward of the points of the heels, said projections having bearing or ground contacting portions in the same 25 plane as the depending walls of the toe pocket and providing additional means for the reception of snow, dirt, etc., to form bearing or wear surfaces.

2. As a new article of manufacture, a 30 horseshoe of the usual shape having a body portion of substantially uniform thickness throughout its entire extent, said shoe having a pocket centrally of the toe portion of the same formed by a continuous wall 35 depending from its under surface; said wall being integral with said shoe and having lateral and transverse portions; the latter following the contour inner and outer line of the shoe and providing an isolated pocket 40 for the reception of snow, dirt, grit, etc., to form a bearing or wear surface, the quarters of said shoe being unobstructed rearwardly from said toe pocket, with calks or projections depending from said quarters forward 45 of the heel points and of equal depth with the depending walls of the toe pocket.

3. A horseshoe having its lower face provided at toe and heels with depending pro-

jections of equal depth forming inclosing and retaining means to receive and retain 50 snow or dirt to form a gripping surface for the shoe; the quarters intermediate said depending portions being unobstructed and having nail holes set inwardly a sufficient distance to avoid collapse or displacement 55 when the shoe is manipulated or reshaped to fit a hoof.

4. As a new article of manufacture, a horseshoe of the usual shape having a body portion of substantially uniform thickness 60 throughout its entire extent, said shoe having a pocket at the toe portion of the same formed by a continuous wall depending from its under surface, said wall being integral with said shoe and providing an isolated pocket for the reception of snow, dirt, grit, etc., to serve as a bearing or wear surface, the quarters of said shoe being unobstructed rearwardly from said toe pocket whereby manipulation of the same to fit 70 variously shaped hoofs may be readily accomplished, and projections depending from said quarters forward of the heel points and having contacting surfaces in the same plane as the depending walls of the toe pocket. 75

5. As a new article of manufacture, a horseshoe of the usual shape and of substantially uniform thickness throughout its entire extent, with a toe pocket depending therefrom and formed by a plurality of 80 walls integrally connected together and to said shoe, said pocket occupying the forward central portion of the shoe whereby substantially unobstructed quarters are left for manipulation to fit variously shaped hoofs, 85 the toe pocket serving to collect dirt, snow, etc., and provide a bearing or wear surface, and said quarters terminating in separate heels, and projections depending from each of said quarters forward of the heel points 90 and providing pockets having contacting surfaces in the toe pocket for the reception of snow, dirt, grit, etc., to form bearing or wear surfaces.

CHARLES A. CAMPBELL.
